UNITED STATES PATENT OFFICE.

JOSEPH HUEBSCH, OF MILWAUKEE, WISCONSIN.

HEATED HOSIERY-FORM.

1,223,585.

Specification of Letters Patent. Patented Apr. 24, 1917.

Application filed June 8, 1914. Serial No. 843,659.

To all whom it may concern:

Be it known that I, JOSEPH HUEBSCH, a citizen of the United States, and a resident of the city of Milwaukee, in the county of Milwaukee and State of Wisconsin, have invented certain new and useful Improvements in Heated Hosiery-Forms; and I do hereby declare that the following is a full, clear, and exact description of the same, reference being had to the accompanying drawings, and to the numerals of reference marked thereon, which form a part of this specification.

This invention relates to a form for hosiery which is internally heated, so that hosiery which has been washed may be stretched upon the form and dried, thus insuring retention of the original shape of the article. The device is particularly applicable in laundries, and where so used, generally a large number of the devices are mounted upon a suitable frame with a common steam line connected to all thereof for heating the same.

My invention can be used very efficiently as an ironing device for hosiery which is already dry, the narrow or flat construction of the form serving admirably for the purpose, it merely being necessary to draw the article over the heated form and allowing it to remain thereon for a short time.

It is an object of this invention to construct a steam heated hosiery form provided with suitable regulating connections for controlling the inlet and outlet thereto.

It is also an object of this invention to construct a steam heated hosiery form provided with an adjustable heel portion, adapting the form to be used for hosiery of different sizes.

It is furthermore an object of this invention to construct a hollow metal hosiery form of high heat conductivity with a pipe running therethrough to admit steam into the interior thereof, and with an outlet for the condensed steam.

It is finally an object of this invention to construct a hosiery form provided with an adjustable heel portion and internally heated to dry hose stretched thereover.

The invention (in a preferred form) is illustrated in the drawings and hereinafter more fully described.

In the drawings:

Figure 1 is an elevation of a rack on which a plurality of hosiery forms embodying the principles of my invention are mounted.

Fig. 2 is an enlarged side elevation of one of said forms showing the valved inlet and outlet connections thereto.

Fig. 3 is an enlarged central vertical section taken through one of the forms on line 3-3 of Fig. 1.

Fig. 4 is a transverse section taken on line 4-4 of Fig. 3.

As shown in the drawings: The form consists of an integrally connected foot portion 1, and leg portion 2, the same being hollow or tubular and forming an integral part of the extended tubular portion 3, which is flanged on its outer end and rigidly secured to a supporting plate or closure 4, in any suitable manner. A nipple 5, is formed on the inner surface of said supporting plate 4, and threaded therein and extending axially through the interior of the form is a steam pipe 6.

A short inlet steam pipe 7, is threaded into said supporting plate 4, communicating with the nipple 5, and is provided with a valve 8, to control the admission of steam to the steam pipe 6, within the form from any suitable supply line 9. An eduction pipe 10, for the water of condensation is also provided, threaded through a suitable aperture in the supporting plate 4, of the form and provided with a valve 11, to control the flow therethrough into the main eduction line 12. A rounded heel member 13, fits closely over and is slidably mounted on said form, and is provided with a pin 14, which engages in a slot 15, in the walls of the foot portion. The common supporting plate 4, for the respective forms is rigidly secured upon the upper end of a standard 16, which is in turn secured on a heavy base 17, to give the entire device stability, and, if desired, pipes may be placed within the standard 16, to communicate with the respective steam and eduction pipes 9 and 12, at the upper end thereof.

The operation is as follows:

An operator desiring to iron or dry the hose draws the same over the toe of the foot portion 1, of the form with the heel of the hose positioned on the upper side of the form. Generally the heel member 13, which is slidable upon the form, will properly position itself for the particular length of the hose, but in the event that this does not take place, the operator may easily adjust the heel member by manipulating the same beneath the hose stretched thereover until said heel member is in proper position.

I am aware that various details of construction may be varied through a wide range without departing from the principles of this invention. I therefore do not 5 purpose limiting the patent granted otherwise than necessitated by the prior art.

I claim as my invention:

1. A device of the class described comprising a hollow form curved to form foot and 10 leg portions, a steam pipe extending axially through said hollow form and open at its end to admit steam thereinto to heat the same, a slot in the wall of said form out of communication with the hollow interior 15 thereof, a heel piece slidable on said form and heated thereby, and means engaging said heel piece to the form through the slot in the wall thereof.
2. In a device of the class described, a hollow internally heated hose form having a slot in the wall thereof out of communication with the hollow interior of the form, a heel member mounted slidably upon the outer surface of said form, and a pin secured 25 in said heel member and engaging in said slot to hold the heel member in position and permitting adjustment thereof.
3. In a device of the class described, a hollow internally heated hosiery form comprising a curved leg and foot portion, a steam admission pipe disposed axially within the form and open at its end to admit steam thereinto and conforming to the curvature of said form, said hosiery form relatively thin in cross section and terminating 30 in relatively sharp edges, and a heel piece having an acutely angled groove therein to fit closely over one edge of said form to receive heat therefrom and slidably mounted 35 for adjustment thereon.
4. A device of the class described comprising a hollow form, means extending axially therethrough to admit steam thereinto to 40

heat the same, said form relatively thin in cross section and terminating in sharpened 45 edges, a heel member acutely grooved to fit over one of said sharpened edges capable of sliding on the form into different positions of adjustment and adapted to receive heat from the form, and a pin and slot affording 50 the connection between said form and heel piece.

5. In a device of the class described a heated hose form terminating in sharpened edges, and a tapered slideable heel piece 55 thereon heated by the heat from said form.

6. In a device of the class described, comprising a hollow curved form relatively thin in cross section and terminating in sharpened edges, a supporting plate thereon, a heel 60 member slidably mounted on one of said sharpened edges with the outer surfaces of said heel member tapering to conform to the taper of the surfaces of the form, and also terminating in a sharpened edge aligned with 65 one of the sharpened edges of the form, and means secured to the interior of said supporting plate and extending within said hollow form to heat the same whereby heat is conducted from said heated form to said 70 heel member.

7. In a device of the class described, a hollow form, means for heating the same on the interior thereof, said form of relatively thin cross section and terminating in sharpened edges, and a heel piece slidably mounted 75 on said form and having a sharpened edge aligned with one of the sharpened edges of said form.

In testimony whereof I have hereunto subscribed my name in the presence of two subscribing witnesses.

JOSEPH HUEBSCH.
